(57) **CLAIM**

The ornamental design for arm for wafer transportation for manufacturing semiconductor, as shown and described.

DESCRIPTION

FIG. 1 is front perspective view of an arm for wafer transportation for manufacturing semiconductor illustrating my new design;

FIG. 2 is a top plan view thereof;

FIG. 3 is a bottom view thereof;

FIG. 4 is a front view thereof;

FIG. 5 is a rear view thereof; and,

FIG. 6 is a left side view thereof, the right side view being a mirror image.

The broken lines in the drawings form no part of the claimed design.
